UNITED STATES PATENT OFFICE.

MICHEAL SHAY, OF OYEN, ALBERTA, CANADA.

HORSESHOE.

Application filed December 31, 1923. Serial No. 683,701.

This invention has relation to certain new and useful improvements in a horseshoe, and has for its primary object the provision of a demountable shoe which is automatically adjustable to the hoof and may be readily secured in position by an inexperienced person without training as a blacksmith.

The invention has for another object the provision of an adjustable demountable shoe 10 of such construction that the sections thereof may be readily connected at the front of the shoe and drawn together at the rear portion thereof until firmly clamped on the hoof, the clamping members permitting of 15 complete adjustment of the shoe.

With the foregoing and other objects in view as will appear as the description proceeds, the invention consists in the novel construction, combination, and arrangement 20 of co-operating elements as hereinafter more specifically set forth, claimed, and shown in the accompanying drawings forming a part of the present application, in which:—

Fig. 1 is an elevation of the shoe applied; 25 Fig. 2 is a bottom plan of the shoe removed;

Fig. 3 is a front elevation of the shoe;

Fig. 4 is an enlarged detail section substantially on the plane of line 4—4 of Fig. 2, 30 looking in the direction indicated by the arrows;

Fig. 5 is a view similar to Fig. 1, showing a modified form of the invention;

Fig. 6 is a bottom plan of the modified 35 form; and

Fig. 7 is a detail section, showing a slight modification and disclosing a manner of adjustably mounting the clamping members.

Referring more in detail to the drawings, 40 in which similar reference characters designate corresponding parts throughout the several views, it will be noted that the horseshoe includes two arcuate sections 10 having reduced overlapping front ends 11 with 45 their opposed faces 12 oppositely beveled and held in engagement with one another by the pivot 13 extended through the reduced ends 11. This may be clearly seen in Figs. 2 and 3. Each shoe section 10 has a plurality of inwardly inclined clamping members 14 provided along its outer edge for engagement over the inclined face of the hoof 15 to which the shoe is applied, as 50 shown clearly in Fig. 1. A number of calks 16 are carried on the under face of each shoe section 10 and are preferably conical with

upstanding shanks 17 threaded in the shoe sections 10, in line with the clamping members 14, as shown in the drawings. The construction and mounting of the calks 16 60 may be varied, if desired, and they may be located at any suitable points along the shoe sections 10. The shoe sections 10 have flattened rear end extensions 17 which are normally parallel. A connecting rod 18 is employed to adjustably connect the rear ends of the shoe sections 10 and firmly hold the shoe on the hoof 15. The offset ends 19 of the connecting rod 18 are extended through suitable openings in the extended rear ends 17 70 of the body sections 10, as shown clearly in Fig. 2. A head 20 is carried on one end of the connecting rod 18 and a nut 21 is threaded on the other end to co-operate with the head 20 in drawing together the extended 75 rear ends 17 of the shoe sections 10 and tightening the shoe on the hoof 15.

In the modified form of the invention disclosed in Figs. 5 and 6, double clamping members 14^a are employed on the rear portions of the shoe sections 10. This form also discloses upstanding lugs 22 on the rear ends of the shoe sections 10, with the offset ends 19 and connecting rod 18 extended therethrough, thus raising the connecting 85 rod 18 above the shoe sections 10 and eliminating danger of the connecting rod 18 striking upon the surface over which the animal is traveling.

By referring to Fig. 7 it will be seen that 90 the clamping members 14 (or 14^a) may be adjustably mounted on the shoe sections 10 for adjustment transversely thereof, by means of set-screws 23 extended upwardly 95 through the shoe sections 10 and through elongated slots 24 in the base portions 25 of the clamping members 14 (or 14^a). It is to be seen that the base portions 25 rest in pockets or recesses 26 provided in the upper face of the shoe sections 10; and counter-sunk recesses 27 are provided in the upper faces of the base portions 25, around the slots 24, to receive the nuts 28 threaded on the upper ends of the set-screws 23. It is therefore evident that the clamping members 14 (also clamping members 14^a), may 100 be readily adjusted and securely fastened in adjusted position.

It is believed the complete construction and mounting of the shoe may now be apparent from the foregoing paragraphs taken 110 in connection with the accompanying

drawings, without further detail description. It may be briefly stated, however, that the shoe may be readily mounted on and adjusted to hoofs of different sizes by an inexperienced person without training as a blacksmith and without the use of the tools ordinarily required for applying and removing the conventional form of horse-shoe now in general use. Furthermore the shoe may be removed and repaired or replaced without loss of time. By constructing the shoe in the manner disclosed in this application, the necessity of providing different sizes and shapes of shoes for different animals is eliminated. It is only necessary to make several different sizes in order to fit the different size and shaped hoofs, as each shoe may be adjusted to a number of different hoofs. Attention is also directed to the fact that the shoe sections 10 will be at all times held firmly together at their pivoted front portions, owing to the beveled faces 12 previously described.

While the preferred embodiment of the invention has been disclosed, it is to be understood that minor changes in the details of construction, combination, and arrangement of co-operating elements may be resorted to within the scope of what is claimed, without departing from the spirit of the invention.

What I claim as new is:

A horseshoe including arcuate shoe sections having overlapping ends, means for pivotally connecting said overlapping ends, adjustable hoof-clamping members carried by said shoe sections, means for drawing together said shoe sections and tightening the same on the hoof including a connecting rod having offset portions engaged through extensions on said shoe sections and calks carried by said shoe sections.

In testimony whereof, I affix my signature.

MICHEAL SHAY.
